SMOKING PIPE

Edward A. Herr, Philadelphia, Pa.

Application August 11, 1937, Serial No. 158,606
Renewed May 14, 1940

2 Claims. (Cl. 131—194)

This invention relates to smoking pipes, and has for an important object thereof the provision of a dry pipe, that is to say, a pipe wherein the lower portion of the bowl will remain dry and, accordingly, a pipe in which a clean cool smoke can be enjoyed to the full extent of the normal charge, and is a continuation in part of my prior application Serial No. 118,128, filed December 29, 1936, for "Smoking pipe."

Many attempts have been made to produce a pipe of this character, but these attempts have failed due to the fact that certain conditions always present in a smoking pipe have either been overlooked or ignored. Saliva enters the stem of a smoking pipe through the bit thereof due, principally, to the fact that there is involuntary and unnoted respiration into the bit which forces the secretion along the bore of the bit and finally from the end thereof. If this secretion collects against the upper wall of the bore, as it readily does due to the fact that it frequently bubbles from the end of the bit, it will creep along this wall and reach the conduit to the bowl without regard as to whether this conduit be disposed at such upper wall or not. Furthermore, such respirations are often of sufficient force to cause the secretions to be carried bodily to the orifice and pass therethrough. Provision of collection cavities or absorption means are of little avail unless these two factors are taken into consideration. A common form of trapping device consists of a bulbous tip for the bit having minute openings therein and, obviously, such openings invite capillary movement of the liquid to the outer surface of the bulb where even a relatively slight respiration would tend to blow the same against the upper wall of the stem duct.

An important object of this invention is the provision of a construction such that engagement of the saliva with the upper wall of the duct is, to the greatest possible extent, eliminated so that a conduit communicating with such upper wall may be disposed out of the general path thereof, and to further construct the pipe so that even a sharp respiration cannot drive the liquid particles, which under such respiration normally tend to spray, to a position adjacent the mouth of such conduit. While these precautions will substantially entirely eliminate bowl moisture in the pipe, I have found that even they will not suffice to keep the bowl completely dry since a certain amount of moisture through bubbling of the viscous saliva at the bit inlet comes in contact with the walls of the

stem and, creeping along the walls, finally arrives at the opening of the duct and is finally ejected through the duct of the bowl. A further object of the invention is, accordingly, the elimination of the possibility of this type of transfer of fluid to the bowl.

These and other objects I attain by the construction shown in the accompanying drawing in which

Fig. 1 comprises a side elevation, partially in section, of a smoking pipe constructed in accordance with my invention;

Figs. 2 and 3 show various modifications of the duct mounting in the stem; and

Fig. 4 is an enlarged view of a portion of Fig. 1.

Referring now more particularly to the drawing, the numeral 10 generally designates the bowl of a pipe which is provided with a stem 11 differing from the usual stem in that the cavity thereof is both longer and of considerably greater diameter than such cavities usually are, being preferably in the form of a straight bore of a size at its outer end to take the neck 12 of the bit 13.

A downwardly and inwardly inclining opening 14 is formed through the wall of the bowl immediately above the upper surface of the stem 11 and adjacent thereto, and at the approximate center of the upper surface of the stem an opening 15 is formed. A small conduit 16, bent in substantial L-shape, has its inner end engaged in the port 14 and its outer end engaged in the opening 15, this conduit being preferably of relatively small bore, and so constructed that it may be readily removed for cleaning.

The bit neck 12, which, as previously stated, closely fits the wall of the conduit, has a considerably reduced, centrally disposed extension 17 through which the inner end of the bit bore 18 opens centrally. The reduction in size of the extension 17 is such that a very considerable space 19 is provided between the wall of the stem cavity 20 and the outer wall of the extension in order that globules of moisture somewhat inflated by a respiration may, as a general rule, not come in contact with the upper wall and so form a capillary bridge permitting fluid to pass along the upper wall of the pipe and so to the opening 15. The inner end of this extension is sufficiently spaced from the opening 15 that the moisture in the air will tend to separate and fall to the bottom of the cavity 20 before reaching the opening, thus avoiding a moist area in the vicinity of this opening. This tendency of the moisture in the air to separate is materially in-

creased by reason of the fact that the opening 15 is disposed well away from the blind inner end of the cavity 20, providing a dead air space 21 of considerable volume which forms a cushion 5 against the inrushing jet checking the velocity of the same and increasing its tendency to expand in the relatively more highly heated chamber formed by the cavity and thus permit separation of its liquid content. The size of 10 this dead air space further insures a collection bowl for liquids moving along the lower wall of the bore which is well spaced from the point of communication with the bowl and thus insures against creeping of the moisture to the conduit 16 15 along which, due to the size of the bore, it would readily move by capillary attraction.

I have found that utilization of these elements in combination in a smoking pipe provides a cool, clean, dry smoke altogether free from the unpleasant experiences usually accompanying 20 smoking of the ordinary smoking pipe. I am aware that the use of by-passes of the type shown at 16 has been previously considered, but in all 25 constructions of this character with which I am familiar the disposition of the remaining portions of the structure has been such that construction of the pipe in accordance with the previous proposals results in relatively rapid collection of moisture in the pipe bowl.

30 As hereinbefore noted, there is a tendency of bubble-transmitted fluid to creep along the upper wall of the cavity 20 and in order to prevent this moisture from passing through the tube 16, I provide an enlarged opening at the mouth of 35 the tube across which the fluid will not bridge and obstruct the passage so that it will be blown into the same. This may be accomplished by employing a tube of normal size, as shown in Figs. 1, 2 and 4, and terminating the end of the 40 tube proper in spaced relation to the inner wall of the stem 11. Since the slight grip of the tube in the wood of the stem would tend to cause rapid enlargement of the opening, the tube is continued by providing in the opening a thin extension of 45 the tube which will remain permanently in position forming a bushing 22 which will not only prevent damage to the stem of the pipe but will provide a smooth wall up which the fluids will not tend to move. The tendency of fluids to collect about the mouth of the tube may be likewise 50 prevented by the extension of the tube into the bore for a short distance, as illustrated at 23 in Fig. 3 and at 23a in Figs. 1 and 4. The same result can be accomplished by employing a 55 relatively large tube 16a having a thick wall and enlarging the bore of the wall at the mouth as indicated at 24. The wall of the enlarged bore at its mouth may be bevelled as at 25 to produce a knife edge which will likewise serve to inhibit 60 the collection of moisture.

65 It will be noted that in each instance there is, in effect, an enlarged continuation of the bore of the tube, the bushings 22 providing this in the one instance and the actual enlargement 24 providing it in the construction shown in Fig. 3.

70 Since the constructions illustrated are capable of some modification without departing from the spirit of my invention, I do not wish to be understood as limiting myself thereto except as hereinafter claimed.

I claim:

1. A smoking pipe comprising a bowl having a

stem provided with a cavity, a bit having a neck fitting the outer end of the cavity and provided with a considerably reduced centrally disposed extension through which the inner end of the bore of the bit opens, said cavity being relatively large in diameter as compared to said extension and said cavity having a blind inner end, the cavity further having an opening in the upper wall thereof, a bushing engaged in said opening at a point disposed substantially midway between the inner end of the cavity and the inner end of the extension of the bit, said bushing having an enlarged upper end limiting its movement into the cavity and having its inner end extending partially into the cavity, a removable tube communicating at one end with the lower end of the bowl and at its opposite end engaged in the bushing, the bore of said tube being considerably less than that of the bushing and the inner end of the tube being disposed outwardly of the inner end of the bushing, the extension of said bit being sufficiently spaced from the walls of the cavity to prevent globules of moisture passing therefrom from normally engaging the cavity wall or being blown against or otherwise engaging the upper portion of the cavity wall, and being further sufficiently spaced from the inlet of the tube to the cavity to permit respiration-borne moisture to separate and flow to the bottom of the cavity, the inner end of the cavity being considerably spaced from the point of communication of the conduit with the cavity whereby to provide a relatively large dead air space beyond the tube from the bit.

2. A smoking pipe comprising a bowl having a stem provided with a cavity, a bit having a neck fitting the outer end of the cavity and provided with a considerably reduced centrally disposed extension through which the inner end of the bore of the bit opens, said cavity being relatively large in diameter as compared to said extension and said cavity having a blind inner end, the cavity further having an opening in the upper wall thereof, a bushing engaged in said opening at a point disposed substantially midway between the inner end of the cavity and the inner end of the extension of the bit, said bushing being so constructed and arranged as to limit its movement into the cavity and having its inner end extending partially into the cavity, a removable tube communicating at one end with the lower end of the bowl and at its opposite end engaged in the bushing, the bore of said tube being considerably less than that of the bushing and the inner end of the tube being disposed outwardly of the inner end of the bushing, the extension of said bit being sufficiently spaced from the walls of the cavity to prevent globules of moisture passing therefrom from normally engaging the cavity wall or being blown against or otherwise engaging the upper portion of the cavity wall, and being further sufficiently spaced from the inlet of the tube to the cavity to permit respiration-borne moisture to separate and flow to the bottom of the cavity, the inner end of the cavity being considerably spaced from the point of communication of the conduit with the cavity whereby to provide a relatively large dead air space beyond the tube from the bit.

EDWARD A. HERR.
